UNITED STATES PATENT OFFICE.

HIPOLIT M. HINCZ, OF CHICAGO, ILLINOIS, ASSIGNOR, BY MESNE ASSIGNMENTS, TO
PATENTED DEVICES COMPANY, OF PORTLAND, MAINE, A CORPORATION OF MAINE.

REINFORCED CONCRETE CONSTRUCTION.

1,173,152.

Specification of Letters Patent. Patented Feb. 22, 1916.

Application filed January 27, 1912. Serial No. 673,794.

To all whom it may concern:

Be it known that I, HIPOLIT M. HINCZ, residing at Chicago, in the county of Cook and State of Illinois, have invented certain new and useful Improvements in Reinforced Concrete Construction, of which the following is a specification.

This invention relates to girderless or flat-slab floors, roofs and similar structures. In prior systems of construction, the metallic reinforcing members have not been economically distributed within the slab, but on the contrary, have been so arranged that in order to obtain sufficient reinforcement in the regions of greatest strain, it has been necessary to use an undue amount of reinforcement in other regions, thereby involving waste of metal.

It is an object of this invention to devise an arrangement of the reinforcing members which shall be consistent with the distribution of stresses in the slab, whereby the metal shall be placed only where needed, and in amounts which are properly proportioned to the duty to be performed.

In certain prior constructions, each floor panel has been considered as consisting of four beams extending directly between columns, with a rectangular slab supported by said beams. Such beams being of long span, require a considerable depth of concrete and therefore if the panel is to be of uniform thickness its thickness will be determined by the thickness required for the beams, thus involving an excessive use of concrete.

One of the objects of this invention is to design the panel in such a manner that a minimum thickness of concrete may be employed.

A further object is to provide, in a system of construction permitting of accurate analysis and determination of stresses, means to transmit the stresses due to the dead weight of and applied load upon the central portion of the panel, more nearly directly to the columns than has heretofore been possible.

One form of construction by means of which the foregoing objects may be attained is illustrated in the accompanying drawings, wherein—

Figure 1 is a fragmental top plan view of a floor embodying the invention. Figs. 2, 3, 4 and 5 are sectional views taken in the

planes of dotted lines 2 2, 3 3, 4 4, and 5 5, respectively, of Fig. 1. For the sake of clearness, some of the reinforcing bars are omitted in Fig. 5.

In the drawings, the numeral 1 denotes columns of any suitable or common construction, and 2 indicates flaring column caps. These caps may be omitted in some instances, as when the spans are short. The columns and capitals may be reinforced in any preferred manner.

While the floor is herein shown as of monolithic construction, it may be considered as made up of a plurality of rectangular panels. Fig. 1 illustrates two complete floor panels and portions of several other panels, each panel being supported at its corners upon the columns. Each panel is considered as comprising a central rectangular slab; four beams arranged in the form of a rectangle surrounding and supporting said slab; cantilevers extending diagonally from the columns to the corners of the rectangle, for supporting said beams; and four elongated slabs extending directly between columns and supported by the beams. The slabs and beams are represented by dot-and-dash lines in the lower portion of Fig. 1, A being the central slab, B the four beams that carry said slab, C the cantilevers, and D the slabs extending directly between the columns.

The slab A may be reinforced in any preferred manner; in this instance I have shown a series of bars 3 extending transversely of the slab, and a similar series of bars 3 crossing the other series at right angles. In the present embodiment, each bar 3 extends from a point near the lower face of one beam B, horizontally through the slab A, thence upwardly and across the opposite beam B and into the adjacent slab D. The bars 3 extend alternately to opposite slabs D.

The reinforcing for the beams B may be of any suitable character, but preferably each of said beams is reinforced by bars 4, as shown in Figs. 1, 2 and 3. These bars extend through the tension region of the beam and thence upwardly and transversely through the upper portion of another of the beams B and into the adjacent slab D.

Each column supports two cantilevers C extending diagonally between columns. Each arm of each cantilever carries one corner of a rectangle formed by the four beams B. In the structure shown as an

example, each cantaliver is reinforced by a group of bars 5 extending within the upper portion of the floor slab, with the end portions of the bars underlying the bars 4 at the intersections of the beams B. Preferably, although not necessarily, the ends of the bars 5 are bent diagonally downwardly at 5^a to assist in caring for diagonal tension. If desired, the extreme ends 5^x of the bars 5 may be bent upwardly into the form of hooks to afford additional anchorage for the bars in the concrete. The bending of the bars 5 as just described affords means for supporting said bars upon the form-work (not shown) during the process of erection, the downwardly bent portions serving as gages to space the body of the bars at the desired distance above the form-work. No material portion of the bars 5 will be exposed upon the under side of the slab, when the extreme ends of the bars are bent upwardly as shown. If desired, the middle portions of the bars 5 in one cantaliver may be deflected or depressed sufficiently to permit both series of bars 5 to lie in the same horizontal plane.

Each slab D is herein shown as reinforced by means of a series of transverse rods 6 lying in the lower portion or tension region of the slab and extending into the adjacent beams B. The slab is further reinforced by the extended portions of the rods 3.

In the completed structure, each beam B supports only one-fourth of the load upon the slab A, together with the load directly above said beam B. The four beams B deliver the major portion of their loads to the cantalivers C, which in turn deliver the load to the columns. Each cantaliver arm is relatively short and is fully counter-balanced by the load upon the opposite arm. The minimum quantity of metal and concrete required in each cantaliver may be readily determined, since it is possible to measure

accurately the stresses to be borne by the 45 cantaliver.

In the embodiment which has been selected for illustration, the panels are rectangular, and the slab A and the set of beams B are accordingly rectangular, but it will be 50 understood that the parts may be of other forms, and that there may be more or less than four beams B, depending upon the shape of the panel.

The embodiment herein shown of the invention is claimed generically in my co-pending application Serial No. 673,793, filed January 27, 1912.

I claim as my invention:

A girderless monolithic reinforced-concrete structure consisting of a plurality of columns and a plurality of concrete slabs over the columns, said columns being located at the angles of the slabs, each slab comprising a central portion, reinforcement 60 for the central portion, reinforcement forming a plurality of beams surrounding and carrying the central portion, said beams having intersecting ends and being arranged in the form of a polygon, reinforcing means 65 over the columns extending diagonally of the slab and forming cantalivers that directly support the ends of the beams at the angles of the polygon, slabs extending directly between columns, the last mentioned 70 slabs being inclosed and supported by said beams, the reinforcement of the central portion extending transversely through the last mentioned slabs, and transverse reinforcement 75 in the tension regions of said last mentioned slabs.

In testimony whereof I affix my signature in presence of two witnesses.

HIPOLIT M. HINCZ.
